United States Patent Office

Des. 221,762
Patented Sept. 7, 1971

221,762

ELECTRIC SPACE HEATER

Alben C. Boggs, Pittsburgh, and Joseph R. Nelis, Wilmerding, Pa., assignors to Emerson Electric Co., St. Louis, Mo.

Filed Apr. 23, 1970, Ser. No. 22,607

Term of patent 14 years

Int. Cl. D23—03

U.S. Cl. D23—111

FIG. 1.

FIG. 3

FIG. 2

FIG. 1 is a front perspective view of an electric space heater showing our new design;

FIG. 2 is a rear perspective view thereof on a reduced scale;

FIG. 3 is an enlarged sectional view taken on line 3—3 of FIG. 2.

We claim:

The ornamental design for an electric space heater, substantially as shown.
